(No Model.)

L. C. MARTIN & J. W. HART.
HEATING STOVE.

No. 393,018.

Patented Nov. 20, 1888.

UNITED STATES PATENT OFFICE.

LYMAN CLARK MARTIN AND JOHN WILEY HART, OF IOLA, KANSAS.

HEATING-STOVE.

SPECIFICATION forming part of Letters Patent No. 393,018, dated November 20, 1888.

Application filed February 9, 1888. Serial No. 263,492. (No model.)

To all whom it may concern:

Be it known that we, LYMAN CLARK MARTIN and JOHN WILEY HART, citizens of the United States, residing at Iola, in the county 5 of Allen and State of Kansas, have invented a new and useful Improvement in Heating-Stoves, of which the following is a specification.

Our invention relates to improvements in heating-stoves; and it consists in certain novel features hereinafter described and claimed.

In the accompanying drawings, Figure 1 is a perspective view with a part of the shell or casing of the stove broken away. Fig. 2 is a 15 vertical section taken at right angles to Fig. 1, and Fig. 3 is a detail view of the ash-pan.

Referring to the drawings by letter, A designates a heating-stove having the usual hearth, B, and grate C at its lower end, and 20 the smoke-pipe D leading from its upper end.

E designates an open-ended tube or pipe extending vertically through the stove, and having its lower end somewhat below the bottom of the stove, and its upper end flush with 25 the top of the stove, as clearly shown. A short distance above the lower end of the tube I provide it with an annular flange, D', through which bolts are passed to secure the tube to the stove.

30 F designates the opening in the grate, through the center of which the tube or pipe E extends, and G is the ash-pan, supported by the hearth beneath the grate. This ash-pan is made in two sections or members, H I, as shown, 35 provided in their adjacent sides with semicircular recesses J K, which fit around the air tube or pipe E, as shown in Fig. 2. One section or member of the ash-pan is drawn out, in emptying, from the front of the stove, and 40 the other one is drawn out from the back of the same, as will be readily understood.

The upper end of the air-tube is provided with a casting, M, upon which I rest the lower ends of a series of concentric heating pipes 45 or tubes, N O P, which extend up through the room to the upper stories of the building. The upper end of the outer tube is arranged flush with the floor of the second story, and is

provided with a register, as clearly shown in Fig. 1. The next inner tube extends to the 50 third story, and is provided with a similar register, and so on.

In practice a fire is built upon the grate in the usual manner, and the smoke and products of combustion are carried off through 55 the smoke-pipe. The fire thus being in direct contact with the central air-tube heats the air in the same, which at once rises and passes from the open top of the same into the room. The place of the air thus leaving the tube is 60 at once filled by the cold air drawn in through the lower end of the tube, which is in turn heated and caused to pass out at the top of the tube into the room. A constant circulation of the air in the room is thus maintained and 65 the air is thoroughly heated. All of the air in the tube will not pass out into the room in which the stove is placed; but a large portion will pass into the rooms above, thus heating the entire building.

70 The air-tube can be made in sections, so as to be readily adjusted to the height of the stove, and, if so desired, it may be carried obliquely through the fire-chamber or formed on the outside of the same.

Having thus described our invention, what we claim, and desire to secure by Letters Patent, is—

The combination, with a heating-stove, of the central air-tube having its lower end arranged below the bottom of the stove and its upper end arranged flush with the top thereof, the casting M in the upper end of the central air-tube, and the concentric pipes having 80 their lower ends resting on the casting M, and 85 each of said pipes having its upper end provided with a register and arranged flush with one of the floors of a building, as specified.

In testimony that we claim the foregoing as our own we have hereto affixed our signatures 90 in presence of two witnesses.

LYMAN CLARK MARTIN,
JOHN WILEY HART.
